DOOR HANDLE ASSEMBLY

Burton S. Floraday, Toledo, Ohio, assignor to Detroit Harvester Company, Detroit, Mich., a corporation of Michigan

Application September 6, 1945, Serial No. 614,632

1. Claim. (Cl. 64—30)

1 This invention relates to a window regulator mechanism but more particularly to a window regulator handle adapted for use in connection with public vehicles such as buses or the like.

Not infrequently the occupants of such vehicles tamper with the handles and turn them with excessive energy which often results in the breakage of the handle or driving spindle. It would be deemed an advantage if the regulator units could be so constructed that the effort necessary to turn the handle could be varied at the will of the mechanic, and if turned the handle could be adjusted to turn independently of the spindle.

An object of this invention is the production of a vehicle window regulator handle which may be easily adjusted to turn with or independently of the enclosed driving spindle.

Another object of this invention is the production of a window regulator handle in which the effort necessary to turn the handle in relation to the spindle may be varied by simple, accessible means.

Other objects and advantages of the invention reside in the details of construction, arrangement and operation as hereinafter described, and for purposes of illustration but not of limitation, an embodiment of the invention is shown in the accompanying drawing in which

Figure 1 is a fragmentary sectional view of the handle and spindle showing the arrangement of the units comprising the invention;

Figure 2 is a sectional view along the line A—A of Figure 1;

Figure 3 is a bottom view of the spindle and sleeve section;

Figure 4 is a plan view of the clutch plate adapted for assembly in the sleeve keyway; and

Figure 5 is a plan view of the clutch plate adapted for assembly in the spindle keyway.

The illustrated embodiment of the invention comprises a crank handle 10 mounted on a spindle 11 and provided with a large cavity forming a sleeve or skirt section 12. The lower inside portion of the sleeve 12 is threaded to engage a similarly threaded collar 13 enclosing the cavity, and adapted for inward or outward adjustment by turning said collar 13 in relation to the sleeve 12. An opening in the center of the collar 13 is sufficiently large to serve as a bearing for the spindle 11 which extends therethrough and permits rotational movement of the collar 13 in relation to said spindle 11. Disposed within the large cavity and about the spindle 11 is a coil spring 14, one end of which abuts the inside

surface of the collar 13, the opposite end bearing against the first of a series of clutch plates 15.

2 Two modifications of clutch plates are used. One type 15a, shown in Figure 4, is disc-shaped with a central opening 17 slightly larger than the diameter of the spindle 11 and an outside diameter slightly less than the inside diameter of the sleeve 12. Two rectangularly shaped flanges 18 extend outwardly from the perimeter of the disc and fit into similarly shaped longitudinal slots 19 in the length of the sleeve such that this group of plates are adapted for longitudinal movement in relation to the sleeve but must, however, rotate with the sleeve 12. The other modification of the clutch plate 15b, shown in Figure 5, is similar to that of 15a other than the two flanges 20 extend inwardly from the perimeter of the central opening and fit into two similarly shaped longitudinal slots 21 in the spindle 11 such that these plates move rotationally only with the spindle but may also be moved longitudinally in relation to the spindle 11. Discs 16 of frictional material are interposed between the plates 15a and 15b which are alternatively disposed about spindle 11, the last of these clutch plates seating against the shoulder 22 formed where the larger cavity of the sleeve continues inwardly as cavities 23 and 24 of progressively smaller diameter, the latter serving as an end bearing in which the spindle 11 rides. The spindle 11 is restrained from independent longitudinal movement by a lock pin 25 which extends through the encircling portion of the handle 10 and rides in the annular groove 26 near the end of the spindle 11.

It is a well-known fact that the effort necessary to move one surface over another increases with increasing pressure between those surfaces. Thus, when the collar 13 is rotated for upward movement, the spring 14 is further compressed creating greater pressure between the clutch plates 15 and the friction discs 16 such that considerably greater effort is necessary to turn the plates 15a in relation to the plates 15b or, similarly, the crank handle 10 in relation to the spindle 11. Likewise movement of the collar 13 outwardly will result in some relaxation of the compressive forces and thus require less effort to turn the crank handle 10. However, the units are independently disposed such that effort expended in excess to that required to overcome the friction between the plates and friction discs merely results in the rotation of one plate in relation to

the other, or similarly, rotation of the crank handle 10 in relation the spindle 11.

It is apparent that I have produced a simple inexpensive means for increasing or decreasing the effort necessary to turn the crank handle of a window regulator and preventing excessive breakage of such units.

It is to be understood that numerous changes in details of construction, arrangement and operation may be effected without departing from the spirit of the invention especially as defined in the appended claim.

What I claim is:

A vehicle window regulator handle comprising a crank arm, a hub integral with the base of the crank arm and extending at substantially right angles therefrom, an elongate sleeve on said hub forming a socket, said hub having an axially disposed socket, a spindle co-axial with said sleeve and fitting said socket, means for holding said spindle in said socket but enabling relative turn-

ing movements thereof, a plurality of disc-like plates on said spindle and disposed within said sleeve and keyed alternatively to the sleeve and spindle, discs of friction material interposed between said plates, a collar in screw-threaded engagement with the inside of said sleeve adjacent the outer end thereof and serving as a bearing for said spindle, and a coil spring bearing respectively against said collar and the adjacent one of said disc-like plates.
